Thomas H. Furman

By *Clarence O'Brien*,
Attorney

UNITED STATES PATENT OFFICE.

THOMAS H. FURMAN, OF RIALTO, CALIFORNIA.

ROPE HOLDER.

Application filed October 25, 1928. Serial No. 314,977.

This invention relates to new and useful improvements in rope holders, generally though not specifically adapted for use in the securing of clothes line ends whereby to permit the line to be tautly arranged between opposite posts, and also to permit the line to be readily detached from the posts when not in use in order that the line may be stored within the house, thus protecting it from the weather. One of the most pertinent objects of this invention is to provide a rope holder of this character that is extremely simple in construction and inexpensive of manufacture and one that is well adapted for rigidly securing the line in taut condition.

Furthermore the invention is characterized by a removable clamp member to permit the line to be quickly and easily associated with or removed from the holder.

From the foregoing and other objects in view as the nature of the invention will be better understood, the same comprises the novel form, combination and arrangement of parts hereinafter more fully described, shown in the accompanying drawings and claimed.

In the drawings wherein like reference characters indicate corresponding parts throughout the several views:

Figure 1 is a side elevation of my rope holder illustrated as having one end of a clothes line or rope associated therewith.

Figure 2 is a front elevation of the holder.

Figure 3 is a perspective of the bracket member per se, and

Figure 4 is a similar view of the movable clamping member.

Now having particular reference to the drawings, my novel holder consists of a bracket member 5 in the form of a casting or stamping constructed to provide a narrow back wall 6 and a pair of spaced parallel side walls 7-7. Said back wall 6 of this bracket is provided at its opposite ends with screw openings to permit the bracket to be screwed or otherwise securely attached to a clothes line post, or other supporting element. The side walls 7 of this bracket are formed with upwardly and inwardly extending hooks 8-8 for a purpose presently to be described.

Furthermore, this holder consists of a clamping lever 9 also in the form of a casting or stamping constructed to provide a narrow back wall 10 and a pair of narrow

side walls 11-11 that merge into the back wall at a point above the lower end of the clamping lever. The back wall is formed throughout its length with a rope receiving channel 10, while this back wall extends forwardly between the upper ends of the side walls 9-9 to provide a curved upper end for the clamping lever. Arranged between the said side walls of this clamping lever beneath the upper end thereof is a pin 12, the ends of which project beyond the side walls for engagement within the hooks 8-8 of the bracket member 6, thus providing a pivotal support for the clamping lever. Loosely attached to the pins between the sides of the clamping lever is a short chain 13 that is in turn secured at its lower end to one of the side walls of the bracket to prevent entire displacement of the lever with respect to the bracket. In actual use, the clamping lever is removed from the hooks of the bracket after which one end of the rope A is arranged downwardly through the bracket. The clamping lever is then arranged in position as illustrated in Figures 1 and 2, and a pull upon the rope beneath the lever will release the same to enable the rope to be pulled between the bracket and the lever. As soon as tension upon the rope beneath the lever is released the lever will swing to the position illustrated in Figures 1 and 2 for clamping the rope between the lower end of the lever, and the rear wall of the bracket as illustrated by the dotted lines in Figure 1. Obviously the rope may be released by pulling outwardly upon the end thereof beneath the lever for rocking the same in a reverse direction. In view of the foregoing description when considered in conjunction with the accompanying drawing it will be apparent that I have provided a novel, simple and useful rope holder that is well adapted for all the purposes heretofore designated, and even though I have herein shown and described the invention as consisting of certain detail structural elements it is nevertheless to be understood that some changes may be made therein without affecting the spirit and scope of the appended claim.

Having thus described the invention, what I claim as new and desire to secure by Letters Patent is:

In a rope clamp of the character described, a bracket consisting of a back wall and a pair of spaced parallel side walls, said bracket

adapted to be anchored to a suitable support, upwardly and inwardly extending hooks formed at the forward edges of the bracket side walls, a clamping lever consisting of a back wall and a pair of side walls, a pin arranged transversely between the side walls of the lever and projecting at its ends beyond said side walls for detachable engagement within said hooks, the lower end of the 10 clamp adapted for binding the rope against

the back wall of the bracket when the rope is passed between the bracket and lever and tension applied to the rope at the upper end of the lever, and a flexible connection between the lever and said bracket to prevent 15 displacement of the lever with respect to said bracket.

In testimony whereof I affix my signature.

THOMAS H. FURMAN.
